UNITED STATES PATENT OFFICE.

JEROME L. TINDALL, OF PUEBLO, COLORADO.

REISSUED

WATER-TUBE STEAM PRODUCER.

1,412,904.

Specification of Letters Patent. Patented Apr. 18, 1922.

Application filed June 28, 1920. Serial No. 392,312.

To all whom it may concern:

Be it known that I, JEROME L. TINDALL, a citizen of the United States, residing at 307 West Fifteenth Street, in the city of Pueblo, county of Pueblo, and State of Colorado, have invented a new and useful Water-Tube Steam Producer, of which the following is a specification.

10 My invention relates to improvements in
water tube steam producers in which there
are three major sections situated with relation
to one another so that there is a saving
of the heat and a complete and efficient cir-
15 culation is provided in all the water tubes
of the system. The water enters these sec-
tions through the economizer section and
then to the steam producer section and
thence to the superheating section.

My objects in this form of water tube steam producer are, first, to arrange the passages for the water through the tubes of the steam producer in such a way that the circulation will be entirely free and unhampered; second, that the heating surface be so arranged that the heat will be absorbed to the minimum of loss; third, that a minimum of space and weight be required for the steam producer; fourth, to produce a steam producer that may be more cheaply constructed and with superior efficiency; fifth, to provide means for removing salts and sediment from the water in the water tubes of the steam producer. I attain these objects by means of the water tube appliances illustrated in the accompanying drawings, in which—

Figure 1, is a plan view of the water tube steam producer, not showing the housing or jacket or the burner; Fig. 2, is a vertical sectional view of the water tube steam producer on the line 2—2 in Fig. 1; and Fig. 3, is an elevation looking at the right side of Fig. 1.

Similar letters and similar numerals refer to similar parts throughout the several views.

The economizer section A consists of a system of small water tubes bent to conform to a rectangular space near the flue or vent 50 for the hot gases and is so placed and provided as to absorb the remaining heat from the escaping warm gases. This system of tubes are welded together in one continuous line of tubing. The feed water is delivered 55 to the economizer section from the feed water pumps through the tube 1, and after

passing through the economizer system is delivered through the tube 2, to the steam generating section B. This tube 2, passes longitudinally through the large cylinder E, and is closed at its extreme end. Within the cylinder E, the tube 2 has a multiplicity of outlets 3, 3, which open into the ends of the downward-extending tubes 4, 4, which pass horizontally under the rest of the pipes of the steam generating section B, and empty into the common header pipe or distributor 5. This distributor 5 is provided at each end with flanged caps 6, removably attached to enable one to clean out the deposited salts and debris that may be precipitated from the heated water. From the distributor 5 the water gradually rises by passing forth and back through the gradually inclined tubes 7, 7, of the steam generating section B, and enters the steam-and-water separating cylinders D and E. The deflector plates 8 and 9, in the cylinder D, and the deflector plate 11 acting with the projecting side of the tube 2, in cylinder E, tend to direct the water across their respective cylinders and cause it, when relieved of its steam which escapes up between said deflectors, to descend again downwardly through the tubes 4, 4, to the distributor.

The water level is maintained in the water tube steam producer at a point near the dotted line 14, and a little above the deflector plates 8, 9, and 11, and above the cross tubes 10.

It is plain, that when the steam escapes between the deflector plates 8, 9, it will leave the water from which it escapes lighter than when it was charged with hot steam, and inclined to pass downwardly and horizontally through the cross tubes 10 to the separating cylinder E, where it is relieved of the rest of its steam, and then has a tendency to being forced downwardly in the pipes 4. 100

The steam is forced upwardly through the pipes 13 and 12, from the separating cylinders D and E, respectively to the steam reserve cylinder F.

The baffle plate 19, protects the economizer section, A, from the very hot gases from the furnace, and preserves the high temperatures for the superheating section C, and reserves the low temperatures in the water in section A, to absorb the depleted temperature from the gases as they are about to be forced through the furnace outlet or

flue. The baffle 20, protects the feed water in the tubes 4 from being excessively heated so that its specific gravity will be enough greater than the waters in the tubes 7 to 5 maintain the normal and uninterrupted circulation therein.

The tube 15 has its upper end tightly inserted into the end of the steam reserve cylinder F, and that part within F, has numerous perforations permitting the steam to enter it to escape into the numerous and continuous tubes of the superheater section C. Tube 15 extends downwardly and conveys the wet steam from the reserve cylinder F to the superheater section C where it enters at the point 16, and after passing back and forth through the continuous line of tubes of the superheater section C, passes out at the point 17 of the tube 18 on its way 20 to the engine.

One of the purposes in having the superheater section away from the hottest gases of the furnace is to prevent its pipes from getting suddenly too hot, as the superheated dry steam will not readily protect the pipes as water or wet steam will. I am aware that prior to this invention water tube steam producers have been invented and used, and therefore I do not claim broadly the system 30 of water tube steam boilers, but, I claim—

1. A water tube steam-producing appliance of the class described, comprising in combination, three tubular sections, the first section disposed at the outlet of the furnace gases, and provided to absorb the remaining heat by contact of the gases with the numerous small horizontal tubes containing the cool water from the supply pipe, the second section comprising numerous horizontally disposed pipes in tiers and provided to generate the steam by contact with the hottest gases of the furnace, two large horizontally-disposed cylinders situate above said second section and extending parallel 40 with the tubes of the first section, which is over one end of the second section, one of said cylinders being over the opposite end of the second section from the first section and the other located near the first section, 45 with the tubes of the first section, which is over one end of the second section, one of said cylinders being over the opposite end of the second section from the first section and the other located near the first section, 50 the space between said cylinders being the passage for the hot gases from the second section to the other sections, a baffle shield extending horizontally under the first section and over the end of the second section 55 and into contact with the side of the nearest cylinder provided to conduct the hot gases from the second section up between said cylinders, and an upright baffle shield extending downwardly from the under side 60 of the other cylinder.

2. In a water tube steam producer of the class described, having three distinct sections in the system, comprising an economizing section at the water supply end of the 65 connected series and a steam generating sec-

tion situate at the under side of the system, and a superheating section above the second section, the combination in the superheating section of an end cylinder, a central cylinder, and an upper cylinder, a baffle shield 70 extending downwardly from the said end cylinder provided to conduct the hot gases up between the end cylinder and the central cylinder, a baffle shield extending horizontally from the central cylinder between the 75 first section and the second section provided to conduct the hot gases from the second section up between said end cylinder and said central cylinder to the superheating section and said upper cylinder, connecting 80 tubes provided to conduct the water from the side of the central cylinder to the lower side of the end cylinder, downwardly extending tubes having their intake in the side of said end cylinder, a header pipe at the 85 bottom of the second section in the line of the water circulation between said downwardly extending tubes provided for distributing the water received therefrom to the steam generating section, and deflector 90 plates in said end cylinder, just below the water surface in the superheating section, provided for the escape of the steam and for the deflecting of the water back into the circulation of the said second section. 95

3. In a water tube steam producing system of the class described, the combination with a rectangular steam producing section composed mostly of longitudinally disposed water tubes and a common header pipe, and an economizer section of horizontally disposed pipes above one end of the steam producing section and with its pipes extending transversely to those of the under section, of a superheating section located above the 105 opposite end of the steam producing section, and comprising a central cylinder, an end cylinder, an upper cylinder and a plurality of horizontally-disposed steam pipes all extending transversely to the water tubes of 110 the steam producing section, a baffle shield extending downwardly from the said end cylinder, and a baffle shield extending horizontally from the said central cylinder and under the economizer section and both 115 baffles provided to conduct the hot gases up between the said end cylinder and the said central cylinder to the superheating section, the central cylinder being placed a little above the plane of the end cylinder, feed 120 pipes from the steam producing section entering the central cylinder, cross pipes conducting the water from the central cylinder to the end cylinder, deflectors horizontally extending toward each other from the inside of the central cylinder below the water surface and provided to direct the water toward the said cross pipes and to allow the steam to escape from between said deflectors 125 upwardly, through a connecting steam pipe 130

to the said upper cylinder which is the steam reserve cylinder, a deflector extending from the inside of the end cylinder horizontally and provided to direct the flow of water 5 from said cross pipes downwardly into the pipes connecting with said header pipe, steam connecting pipes connecting the end cylinder with the said upper cylinder, and a perforated small tube longitudinally secured 10 within said upper cylinder and having an outlet pipe conducting the dry steam from it to the tubular circulation of the said horizontally-disposed steam pipes in direct train to the engine.

15 4. In a steam producing system of the class described, the combination with a steam producing section and baffle shields provided to conduct the hot gases to a certain location above said section, of a superheating 20 section located in contact with the outlet from said baffle shields and comprising a central cylinder, an end cylinder and an upper cylinder and interlocated steam pipes extending parallel with said cylinders, a 25 feed-water pipe conducting the water and entering into one end of the end cylinder and being closed at its extremity and having holes in its side provided to allow the feed-

water to pass into the end of downwardly extending pipes entering the said end cylinder and the holes in the end of said pipes registering with the holes in said feed-water pipe, cross tubes having their intake within said central cylinder and their outlets in said end cylinder, deflector plates extending 30 toward each other from the inner faces of the said central cylinder and provided to allow the steam in said central cylinder to escape from the water and provided to deflect the current of hot water toward the intake ends of said cross tubes, steam pipes provided to conduct the hot steam from said end cylinder and said central cylinder to said upper cylinder, a wet-steam pipe extending longitudinally into one end of the 40 upper cylinder near its upper wall and having numerous small holes provided as outlets for the wet steam from the upper cylinder through the said wet-steam pipe to the said horizontally-disposed steam pipes provided 45 for the super-heating of the wet steam.
